UNITED STATES PATENT OFFICE

161,655

END PLATE FOR RAILWAY BOXCARS

William C. Sleeman, Birmingham, and Robert F. Karger, Mountain Brook, Ala., assignors to Pullman-Standard Car Manufacturing Company, Chicago, Ill., a corporation of Delaware

Application May 26, 1949, Serial No. 2,893

Term of patent 14 years

(Cl. D66—2)

To all whom it may concern:

Be it known that we, William C. Sleeman, and Robert F. Karger, citizens of the United States of America and residents, respectively, of Birmingham, county of Jefferson, and State of Alabama, and Mountain Brook, county of Jefferson, and State of Alabama, have invented a new, original, and ornamental Design for End Plate for Railway Boxcars, of which the following is a specification, reference being had to the accompanying drawings, forming part thereof.

In the drawings—

Fig. 1 is a general end elevational view of our new design for an end plate for railway boxcars having associated portions illustrated in dotted lines;

Fig. 2 is a fragmentary horizontal sectional view through the end plate showing the sectional contour of the vertical corrugations therein; and

Fig. 3 is a vertical sectional view through the

end plate showing the sectional contour of one of the corrugations in a vertical plane.

The characteristic features of our design reside in the portions shown by means of full lines in the drawing.

What is claimed is:

The ornamental design for an end plate for railway boxcars, substantially as shown and described.

WILLIAM C. SLEEMAN.
ROBERT F. KARGER.
